UNITED STATES PATENT OFFICE.

CALEB GOODWIN, OF EVANSTON, ILLINOIS.

PORTABLE SECRETARY.

SPECIFICATION forming part of Letters Patent No. 645,085, dated March 13, 1900.

Application filed June 2, 1899. Serial No. 719,070. (No model.)

To all whom it may concern:

Be it known that I, CALEB GOODWIN, a citizen of the United States, residing in Evans-
5 ton, in the county of Cook and State of Illi-
nois, have invented a new and useful Portable
Secretary, of which the following is a specifi-
cation.

My invention relates to improvements in
writing-desks or secretaries; and the objects
10 of my invention are to provide a secretary
which shall not be greater in size than an ordi-
nary sample-case, which being very light
can be easily carried by a handle secured to
its upper end, and which can be set up, opened,
15 and used anywhere. I attain these objects by
the mechanism described below, and illus-
trated in the accompanying drawings, in
which—

Figure 1 is a front elevation of my improved
20 portable secretary. Fig. 2 is a detail section
of the same on the line 2 2 of Fig. 1, looking
in the direction of the arrow, the secretary
being closed. Fig. 3 is a similar section on
line 3 3 in Fig. 1, looking in the direction of
25 the arrow, the secretary being open. Fig. 4
is a perspective view of the complete secre-
tary open and ready for use. Fig. 5 is a de-
tail plan section taken on line 5 5 of Fig. 3.
Fig. 6 illustrates a part of one side of the case,
30 showing one of the grooves 15 15.

Like numerals refer to like parts through-
out the several drawings.

Referring to the drawings, 10 is the case,
11 the door, and 12 the leaf of the secretary.
35 The case is an open wooden frame having
strong canvas 12 $\frac{1}{2}$ stretched upon and secured
by any suitable means, as the tacks 12', to
the back, top, bottom, and sides of the case.
The depth of the case will be usually four
40 inches, but may be made greater or less, as
found convenient.

The door is formed of wood and is also cov-
ered on its outer side with strong canvas 12 $\frac{1}{2}$,
secured by the tacks 12'. It is hinged to the
45 case so as to close the same. It is fastened
when closed by the lock 13.

The shelf 14 is secured in the case in the
grooves 15 15 near the top of the case.

The leaf is secured by the hinges 16 16 to
50 the lower side of the shelf near its front edge.

A bracket 17 is pivoted to the inner face
of each side of the case just below the shelf.

This bracket has the notch 18 in the lower
side near its outer end. The bearing 19 is se-
cured on the under side of the leaf at such a
point that the bracket passing through it will
cause the notch to engage with it, so as to
support the leaf at the proper angle for use
in writing. This bearing may be of curved
wire secured to the leaf by any suitable means. 55
60

The bar 20 is secured to the sides of the
case so as to form a receptacle for a letter-file
or other suitable adjunct of a writing-desk.

The pouch 21 is secured in the door for the
purpose of holding paper and envelopes. 65

22 is a receptacle pivoted upon the shelf to
hold an ink-bottle, and 23 is a wire spiral se-
cured upon the shelf to retain a penholder.

24 is the handle, secured upon the upper
end of the secretary to be used in carrying the
same. 70

The case and door may be lined with stiff
paper, and leather may be used instead of can-
vas to cover them. The lower edge of the
case and door are made flush with each other. 75
Hence, when the door is open until it is about
at right angles with the case, the secretary
will stand alone, and the leaf being raised and
secured in place by the brackets and their
bearings one can place a seat before it and 80
write upon it.

Having fully described my invention, what
I desire to claim and secure by Letters Patent
of the United States is—

In a portable secretary, the combination of 85
the case, 10, constructed substantially as de-
scribed, and having the grooves, 15, 15, formed
in the sides of the case near its top; the door,
11, hinged to the front edge of one side of the
case, its top flush with the lower surface of 90
the top of the case, and its bottom flush with
the lower end of the case, so as to make the
desk self-supporting when open; the shelf, 14,
secured in the grooves, 15, 15; the leaf, 12,
hinged to the lower side of the shelf near its 95
outer edge; and the two adjustable brackets,
17, 17, secured to the case by any suitable,
well-known means beneath the leaf, so as to
support the same; substantially as and for the
purpose specified.

CALEB GOODWIN.
